TRAIN INDICATION SYSTEM

Filed May 29, 1925

INVENTOR

Gilbert C. Whitney

UNITED STATES PATENT OFFICE.

GILBERT C. WHITNEY, OF NEW YORK, N. Y.

TRAIN-INDICATION SYSTEM.

Application filed May 29, 1925. Serial No. 33,731.

This invention relates to train indication systems in general and has particular reference to indicating the progress of railway trains especially, though not exclusively, on a railroad which requires that both of the track rails be electrically continuous for the return of the propulsion current but which must be sectionalized to permit and provide for the operation of a block signaling system. 10 This present application is a continuation, in part, of my pending applications Serial No. 702,262, filed March 27, 1924, which has matured into Patent No. 1,596,222, dated August 17, 1926, and Serial No. 8,401, filed 15 February 11, 1925, which has matured into Patent No. 1,596,223, dated August 17, 1926; both for train indication systems.

In my application, Serial No. 702,262, I have disclosed a train indication system 20 wherein one of the track rails of a track section is sectionalized by insulated rail joints located at predetermined points to permit the working of a signal system while the other rail is maintained electrically continuous for 25 the return of the propulsion current. In my application, Serial No. 8,401, I have disclosed a train indication system as installed in non-signalled territory and wherein both track rails are maintained electrically continuous 30 for the return of the propulsion current.

In this present application I disclose my invention, using the principles disclosed in my previously referred to applications, as installed on a railroad both of the rails of 35 which are sectionalized to permit the working of a signal system but also made electrically continuous for the return of the propulsion current from track section to track section by means of impedance bonds, all as herein- 40 after explained.

The general objects of this invention are to provide means to indicate the position and progress of trains on the type of track circuit briefly described above and to carry said 45 indications into effect without moving parts.

Another object is to provide a means to automatically shift the phase relation of track circuit currents and without moving parts other than the moving train on said track 50 circuit.

I have provided the accompanying drawing to clearly illustrate my invention and, to the extent possible, I have used the same reference characters indicating similar parts 55 as were used in my prior applications, here-

inbefore mentioned, and it is presumed that reference will be had to said applications.

Referring to the drawing, a track section consisting of track rails 6 and 7, is shown set apart by insulated track rail joints 8, 8^a, 8^b and 8^c. At one end of said track section a track transformer 9 is shown connected to track rails 6, 7, by means of track wires 10 and 11 and resistance 12. Transformer 9 is the medium, when energized by means of 65 wires 14 and 15 from power wires 16 and 17, connected to the source of energy alternator 18, by which appropriate current supply, when a train is not present, is transmitted via track rails 6, 7 to track wires 19 and 20 70 to winding 23 of relay 24. Winding 25 of relay 24 receives energy by means of wires 26 and 27 from power wires 16 and 17. At the ends of said track section I show impedance bonds 13 and 21 connected between 75 track rails 6 and 7. Both bonds have a center tap connection 13^a and 21^a respectively which serve as the means whereby track rails 6 and 7, of adjacent track rail sections, are made electrically continuous for the return 80 of the propulsion current from track section to track section. Relay 24 is the medium, by means of contact 28, whereby the automatic working of a block signal system (not shown) by the train is carried into effect. 85

It will be observed that I have not shown a block signal system and this is because the same is unnecessary to a proper understanding of this invention—for the same reason I have only shown one track section—but it 90 will be understood that adjacent track sections will be constituted similar to the track section described herein. The track circuit outlined above is the well-known two-rail track circuit as used on electrified railways, 95 whether the propulsion current be direct current or alternating current.

Impedance bonds 13 and 21 consist of a few turns of comparatively heavy copper conductor, mounted on a magnetic circuit and 100 form a path of low ohmic resistance between track rails 6 and 7. Each bond is provided with a centre tap connection 13^a and 21^a respectively, at which tap points connection is made to the corresponding centre tap points 105 of the bonds for the adjacent track sections. The turns are so arranged that, when equal quantities of current flow from each track rail 6 and 7 of one track section via the centre tap to track rails 6 and 7 of an ad- 110

adjacent track rail section no magnetic flux is set up in the magnetic circuit—in other words, the magnetic flux set up by current from track rail 6 to the centre tap is neutralized by the magnetic flux set up by current from track rail 7, and vice versa. When, however, current flows from transformer 9 the centre tap is not involved and the path of current flow in bond 13 is from track rail 6 to track rail 7, or vice versa, as will be appreciated, and, therefore, bonds 13 and 21 constitute a path of low ohmic resistance for track circuit operating current from transformer 9. The path of low ohmic resistance via bonds 13 and 21 is increased many times by virtue of the magnetic field surrounding bonds 13 and 21 and, according to the well-known laws of induction, a comparatively high impedance to the passage of alternating current by the magnetic flux is set up in said magnetic circuit. Impedance bonds 13 and 21, therefore, do not constitute a path corresponding to short circuit conditions on the track sections.

My present invention consists in inductively coupling the indication system of my prior application Serial No. 702,262, which has matured into Patent No. 1,596,222, dated August 17, 1926, to the track circuit in the following manner:—A magnetic circuit 43 having winding 44 is connected to track wires 10 and 11 by means of wires 45 and 46 and, when the track section is not occupied by a train, winding 44 receives current from transformer 9. The flow of current in winding 44 is such as to produce a magnetic flux in magnetic circuit 43 in the relative direction of arrow 51. Mounted on the magnetic circuit 43 I show a winding 47 which is included in a circuit which includes winding 35 of inductive coupling 34—this circuit being completed by the wires 48, 49 and 50, and receiving current from transformer 9. The flow of current in winding 47 is such as to produce a magnetic flux in magnetic circuit 43 in the same relative direction as that produced by winding 44—that is, in the relative direction of arrow 51. Owing to the fact that current flow in windings 44 and 47 produce a flux in the same direction (when a train is not present on the track section) in magnetic circuit 43, windings 44 and 47 mutually build up a magnetic field in magnetic circuit 43 and thus retard the flow of current in each other: winding 44 is thus prevented, under these conditions, from forming a low impedance path on track section and transformer 9.

I have explained that winding 35 of inductive coupling 34 is included in a circuit which receives current supply from transformer 9. Inductively coupled to winding 35 I show winding 36 and the current induced by winding 35 into winding 36 is conducted via transmission wires 37 and 38 to and flows through winding 40 of inductive coupling 39.

Inductively coupled to winding 40 is shown winding 41 and connected thereto is shown indication device (in this instance a suitable incandescent lamp) 42. From the foregoing it will be clear that indication device 42 is always energized to a predetermined degree when transformer 9 is energized and said predetermined degree will, for purposes of clearly presenting and describing my invention only, be considered to be insufficient to cause illumination of indication device lamp 42 when the track section is not occupied by a train.

When a train enters the track section, by passing insulated joints 8^b and 8^c, an additional path of current flow from transformer 9 is provided by virtue of the train car wheel, in contact with track rails 6 and 7, forming a shunt on transformer 9, as will be appreciated. By the act of forming a shunt on transformer 9 a shunt is also formed on winding 44, but the shunt on winding 44 is more complete than the effect of said shunt is on transformer 9 (because resistance 12 is included in the shunt on transformer 9) and the current supply from transformer 9 to said winding 44 is reduced. As a result of the reduction in current flow in winding 44 the magnetic flux in magnetic circuit 43 is reduced. Consequent upon the reduction in flux increased current flows from transformer 9 through winding 47 and tends to restore the flux in said magnetic circuit 43. Owing to the fact that winding 35 of inductive coupling 34 is included in the circuit which includes winding 47 increased current is induced from winding 35 to winding 36 and transmitted via wires 37 and 38 and causes increased current supply to flow to indication device lamp 42 and this results in said lamp being illuminated and is accepted as an indication as to the position of the train at the (normal) entrance end of the track section.

As the train proceeds through the track section, in the direction of the arrow, its movement will be evidenced at indication device lamp 42 by increased brilliancy. Said increased brilliancy is brought about by virtue of the fact that the car wheel movement along track rails 6 and 7 gradually cuts out the track rail resistance included in the car wheel shunt on winding 44 thus responsively making said shunt more effective. According as said shunt becomes more effective less current from transformer 9 flows via winding 44 which results in lessened flux density in core 43 and thereafter increased current flows from transformer 9 via windings 47 and 35 with attendant increased induced current supply to lamp 42 all as hereinbefore explained.

Impedance bond 13, in addition to providing means for the return of the propulsion current from track section to track section,

- on electrified railroads as hereinbefore described, also provides a means to limit the variation in the value of current supplied to indication device lamp 42 as the train proceeds through the track section;—in other words, bond 13 acts as a ballast element or permanent shunt on winding 44. That bond 13 should limit the variation in current supplied to the indication device lamp 42 as the train proceeds through the track section will be clear from the following:—Consider first that bond 13 is not present, that the car-wheel shunt is of negligible resistance and that the resistance of each track rail is one ohm—now, with the car-wheel shunt at the left end of the track section the shunt on winding 44 is two ohms because of the two ohms resistance of the included track rails—when the car-wheel shunt has proceeded one fourth of the distance through the section the value of the shunt on winding 44 will be one and one-half ohms because of the resistance of the track rails then included in the shunt—similarly, it will be clear that the value of the car-wheel shunt on winding 44 will be one ohm with the car-wheel shunt at the half-way point, one-half ohm when the car-wheel shunt is at the three-quarter point and so on until the car-wheel shunt reaches the right end of the track section when the shunt on winding 44 can be considered to be a short circuit; in other words, it may be expressed that the variation, as the car proceeds through the track section, follows a straight line law. Now, consider that bond 13 of, say two ohms resistance, is connected in multiple as shown and with values of two ohms rail resistance as before;—in this case with the car-wheel shunt of negligible resistance at the left end of the track section the value of the car-wheel shunt on winding 44 will be the result of two ohms rail resistance in multiple with two ohms bond 13 resistance which is one ohm; when the car-wheel shunt reaches the quarter way mark the value of the car-wheel shunt on winding 44 will obviously be the result of one and one-half ohms rail resistance in multiple with two ohms bond 13 resistance which is 6/7 ohm; continuing, similarly, it will be evident that at the half way point the value of the shunt on winding 44 will be two-thirds ohm, at the three-quarter way point the value of the shunt on winding 44 will be two-fifths ohm and so on until the carwheel reaches the right end of the track section when the shunt on winding 44 can be considered to be a short-circuit, in other words, it may be expressed that the variation follows a curved line law with an increasing rate of change.
- Comparing the case with and without bond 13, we find that the variation in value, while 100% for the track section in each case, is differently distributed—a uniform variation obtaining throughout the section without the bond 13 and a non-uniform variation with the bond 13 which acts to bunch the variation—the rate being greater as the car-wheel shunt approaches the bond and since the amount of current flowing through winding 47 for variably influencing indication device lamp 42 depends on the variation of car-wheel shunt value on winding 44 it will be clear that bond 13 acts as a ballast element to characteristically vary the current supplied to said indication device lamp 42, in fact, a ballast element may be connected, at any point, between track rails 6 and 7 or between wires 10 and 11 or between wires 45 and 46 for suitably variably affecting the current supply to indication device 42 as the car-wheel shunt proceeds through the track section, but I wish it to be understood that, said ballast element in the form and location of bond 13 or elsewhere may be used or omitted without departing from the spirit and scope of my invention. Obviously, the values used in the above example are simply illustrative and are given only for the purpose of clearly describing the ballast effect of bond 13.
- Resistance 12 is an element included in the energy supply circuit of the well-known A. C. track circuit to prevent an excessive flow of current from transformer 9 when the car wheel shunt is on the track rails at the point where said transformer 9 is connected to the track rails and since said resistance acts to limit the flow of current from said transformer 9 to said track rails and car wheel shunt transformer 9 immediately becomes available as a source of energy supply for the train indication system. Said resistance 12 also performs the function of limiting the flow of current, induced into winding 44 by winding 47 (under the conditions hereinbefore explained) through transformer 9 and winding 47 and thus transformer 9 is limited in value as a path for said induced current and, therefore has less effect on the indication system after said induced current begins to flow from winding 44.
- Hereinbefore, for the purpose of clearly describing my invention only, I have explained that the indication device lamp 42, though always energized, did not receive enough energy to, even slightly, illuminate said lamp when said track section was unoccupied and that, as said train entered said track section, said lamp would be illuminated and with responsive increase in brilliancy as the train proceeded through said track section, but I desire it to be understood that said lamp may be nominally partially lighted when the track section is unoccupied, and then increase in brilliancy in synchronism with the appearance and progress of the train through the track section.
- I direct particular attention to the fact

that, whereas my Patents Nos. 1,596,222 and 1,596,223, function on the basis of change in the rate of current flow directly from transformer 9 through the car wheel shunt, this invention functions on the basis of the car wheel shunt forming a short circuit on winding 44 as will be clearly evident from a consideration of the fact that my invention will function to show position and movement of the train even though no current is supplied to the track rails directly by transformer 9. That my indication system will function to show position and movement of a train on the track circuit even though no current is supplied to the track rails directly by transformer 9 will be clear from a consideration of the fact, hereinbefore set forth, that the train forms a shunt on winding 44 which shunt includes variable amounts of track rail resistance according as the shunt (train) occupies one position or another on the track circuit. Obviously, the train shunt is more effective on winding 44 than on transformer 9 (because of resistance 12 being included in the train shunt effect on transformer 9). Resistance 12, therefore, provides that in every instance, for the case illustrated, the potential difference between wires 10 and 11 on the track rail side of resistance 12 will be lower than on transformer 9 side of resistance 12 and progressively lower as the train shunt moves in the direction of the arrow, on the track circuit. It is apparent that resistance 12 is not essential to the shunt on winding 44, but resistance 12 is essential to prevent a short-circuit on transformer 9 by the train shunt and is also necessary to provide a sufficient current flow to provide for track relay 24 operation. Now, in the event that resistance 12 is broken, or removed, the current supply directly from transformer 9 to the track rails, and the associated potential difference across winding 44, hereinbefore referred to, will cease, but according to the well-known law of mutual induction, winding 44 will become a secondary winding to winding 47. In this case winding 44 becomes a source of current supply to the track rails which track rails are then included in series with said winding 44. The track rail resistance at any time included in series with winding 44 determines the impedance of winding 47 and, therefore, the rate of current flow to winding 35 of inductive coupling 34. The progress of the train, in the direction of the arrow, on the track rails acts to include progressively less track rail resistance in the circuit with winding 44, thus lowering the impedance of winding 47 and whereby synchronously more current flows to winding 35 of coupling 34, eventually to be reflected in the indication device 42, as hereinbefore described. This feature of functioning by virtue of short-circuiting is of particular value on track circuits of the

type which employ impedance bonds because such track circuits require a comparatively high current input when the track section is not occupied and only a small increase in current input can be economically permitted when the track section is occupied. The foregoing warrants the statement that this invention functions properly independent of the regular current supply impressed on the track rails for track circuit relay operation. 75

I have, hereinbefore, pointed out that the current induced from winding 47 into winding 44, under the conditions of track circuit shunt, is displaced in time phase relation to that initially flowing in winding 47 and that part of said induced current flows via transformer 9. Part of said induced current also flows in the circuit including windings 47 and 35 with the current from transformer 9 and, according to well-known electrical laws, two currents displaced in time phase relation combine to produce a current having a wave shape possessed by neither originally and as the resultant wave is a response to the changed conditions brought about by the presence and movement of a train on the track section producing a shunt of various values on said winding to bring about said phase displaced current—then the statement is warranted that the current transmitted to the indication device is synchronously characteristic of the movement of said train on said track section. 90

It is clearly obvious, that various types of alternating current track circuits of the single and double rail type, whether for use on steam railroads or on electrified roads with either alternating current or direct current propulsion, may be employed with my invention, by making the obvious appropriate changes well known to anyone ordinarily skilled in this art, and I desire to have it understood, therefore, that I do not limit myself to the arrangement and illustration which I have shown and described as it is merely illustrative and does not exhaust the various embodiments and forms coming very clearly within the breadth and scope of the broad principles underlying my invention. 100

Having thus described my invention I claim and desire to secure by Letters Patent:

1. In a train indication system, a track circuit including a source of energy, a plurality of impedance bonds connected in parallel with the track rail part of said track circuit, and indication means inductively coupled to a circuit which is connected in parallel to said track circuit and synchronously responsive to the presence and movement of a train on said track circuit. 115

2. In a train indication system, a track circuit including a source of energy, a coupling comprised of two windings in inductive relation to each other, one of said windings connected in parallel with said track circuit 120

and the other winding connected to said source, and an indication device included in the circuit with one of said windings, said device synchronously indicating the presence and movement of a train on said track circuit.

3. In a train indication system, a track circuit including a source of energy, a circuit including a winding and an indication device receiving current from said source, 10 and a winding in inductive relation to said first mentioned winding and capable at times of receiving current from said source and at times of transmitting current to said source, the change between times being effected by 15 a train on said track circuit, the second mentioned winding connected in parallel with said track circuit.

4. In a train indication system, a track circuit including a source of energy, a resistance connected in series in said energy supply to said track circuit, two windings in inductive relation to each other and connected to said source, and indication means included in the circuit with one of said windings, the other of said windings being connected in parallel with said track circuit, said means synchronously indicating the presence and movement of a train on said track circuit.

5. In a train indication system, a track circuit including a source of energy, two windings in inductive relation to each other and connected to said track circuit, both of said windings at times carrying currents in the same time phase relation, one of said windings at times carrying current induced therein by the other of said windings, and an indication device responsive to increased current flow in one of said windings, said increased current flow and the change between said times being effected by a car-wheel shunt on said track circuit.

6. In a train indication system, a track circuit including a source of energy, two windings in inductive relation to each other and connected to said source, said windings at times mutually acting to retard the flow of current in each other and at times mutually acting to increase the flow of current in each other, and an indication device responsive to said currents included in the circuit with one of said windings, the change between said times being effected by a car-wheel shunt on said track circuit, one of said windings connected in parallel with said track circuit.

7. In a train indication system, a track circuit including a source of energy, two windings in inductive relation to each other and connected to said source, said windings at times mutually assisting to retard the flow of current in each other and at times mutually assisting to increase the flow of current in each other, the change between said retard effect and said increase effect being initiated by a car wheel shunt on said track circuit,

and a device responsive to indicate said change, one of said windings being connected in parallel with said track circuit.

8. In a train indication system, a track circuit including a source of energy, a resistance connected in said energy supply to said track circuit, a winding and an indication device connected in series to said source, and a winding in inductive relation to the first mentioned winding, the second mentioned winding connected in multiple with the track rail portion of said track circuit and adapted to be shunted by a car on said track circuit, said device synchronously indicating the presence and movement of a train on said track circuit.

9. In a train indication system, a track circuit including a source of energy, a winding and an indication device connected in series and at times receiving variable quantities of current from said source, and a winding in inductive relation to the first mentioned winding and at times acting to oppose current flow in the first mentioned winding, the second mentioned winding connected to said track circuit and adapted to be shunted by car wheels on said track circuit, said car wheels influencing the current flow to said indication device, said device synchronously indicating the presence and movement of a train on said track circuit.

10. In a train indication system, a track circuit including a source of energy, a winding and an indication device receiving current from said source, and a winding in inductive relation to the first mentioned winding and capable at times of modifying the characteristic flow of current to said indication device, both windings adapted to be shunted by a train on said track circuit to modify said characteristic current flow.

11. In a train indication system, a track circuit including a source of energy and adapted to be shunted by a train, a winding and an indication device receiving current from said source, and a winding in inductive relation to the first mentioned winding and adapted to be shunted by said train, said train shunt having various values of shunt effect on said second mentioned winding dependent upon the position of said train on said track circuit, said indication device synchronously responsive to variations in energy flow in said track circuit due to train movement on said track circuit.

12. In a train controlled signal system, a track circuit including a source of energy, a track relay for controlling a block signal system connected to said track circuit and receiving operating current from said source when said track circuit is not occupied by a train, a train indication device inductively coupled to a circuit which is connected in parallel to said track circuit, said device operative to indicate the position and movement of a train

- on said track circuit independent of the current supplied to the track circuit for track relay operation.
13. In a train controlled signal system, a track circuit including a source of energy, a resistance connected in series in the energy supply to said track circuit, one winding of an inductive coupling connected to said source, the other winding of said inductive coupling connected in multiple with the track rails of said track circuit, an indication device included in series with the first mentioned winding, and a ballast element in multiple connection with said track circuit.
14. In a train controlled signal system, a track circuit including a source of energy, a resistance connected in series in the energy supply to said track circuit, one winding of an inductive coupling connected to said source, the other winding of said inductive coupling connected in multiple with the track rails of said track circuit, an indication device included in series with the first mentioned winding, and a plurality of ballast elements in multiple connection with said track circuit.
15. In a train controlled signal system, a track circuit including a source of energy, a resistance connected in series in the energy supply to said track circuit, one winding of an inductive coupling connected to said source, the other winding of said inductive coupling connected in multiple with the track rails of said track circuit, an indication device included in series with the first mentioned winding, and a ballast element in multiple connection with said track circuit, said ballast element providing a non-uniform variation in current supply to said device as a train proceeds over said track circuit.
16. In a train indication system, a track circuit including a source of energy adapted to be shunted by a train, a resistance connected in series with the source of energy, a circuit including a winding of two transformers receiving energy from said source, the other winding of one transformer connected in multiple with the track rail part of said track circuit and adapted to be short-circuited by a train, and the other winding of the other transformer inductively coupled to an indicating device, for indicating the presence and movement of a train on said track circuit.
17. In a train controlled railway signal system, a track circuit including a source of alternating current energy supply connected to one end of said track circuit, a resistance connected in series with said source of energy supply, the secondary winding of a transformer connected to the track circuit between said resistance and the track rail part of said track circuit and adapted to be shunted by a train on said track circuit, and a circuit including the primary winding of said transformer and a signal device connected in multiple with said source of energy between said resistance and said source of energy.
18. In a train controlled railway signal system, a track circuit including a source of alternating current supply connected to one end of said track circuit, a resistance connected in series with said source of current supply, the primary windings of two transformers connected in series and connected to said source between said source and said resistance, the secondary winding of one of said transformers connected to the track circuit between said resistance and the track rail part of said track circuit and adapted to be shunted by a train on said track circuit, and the other winding of the other transformer inductively coupled to an indicating device.
19. In a train controlled railway signal system, a track circuit including a source of energy therefor, a signal device adapted to receive energy from said source, and a circuit controller for providing train control of said device, said controller comprising two inductive couplings, one winding of one inductive coupling bridged across the rails of said track circuit and acting as a choke coil to restrict current flow in the other inductive coupling when said track circuit is not occupied by a train and to permit increased current flow through said other inductive coupling when said track circuit is occupied by a train.
20. In a train controlled railway signal system, a track circuit including a source of energy therefor, a signal device adapted to receive energy from said source, and a circuit controller for providing train control of said device, said controller comprising two inductive couplings, one winding of one inductive coupling bridged across the rails of said track circuit and acting as a choke coil to restrict current flow in the other inductive coupling when said track circuit is not occupied by a train and to permit increased current flow through said other inductive coupling when said track circuit is occupied by a train, said increased current flow having a variable value according as the train occupies one position or another on said track circuit.
21. In a train controlled railway signal system, a track circuit including a source of energy therefor, an indication receiver device, and an indication transmitter comprised of two inductive couplings, one inductive coupling connected to said track circuit and arranged to act as a choke coil to restrict energy flow from said source through said other coupling, for controlling said indication device, unless said track circuit is short-circuited.
22. In a train controlled railway signal system, a track circuit including a source of energy therefor, an indication receiver device, and an indication transmitter comprised of two inductive couplings, one inductive cou-

pling connected to said track circuit and arranged to act as a choke coil to restrict energy flow from said source to said other coupling, for controlling said indication device, unless said track circuit is short-circuited.

23. In a train controlled railway signal system, a track circuit including a source of energy therefor, an indication receiver device, and an indication transmitter comprised of two inductive couplings, one inductive coupling connected to said track circuit and arranged to act as a choke coil to restrict current flow therethrough when said track circuit is not occupied by a train and to assist current flow therethrough when said track circuit is occupied by a train for controlling said receiver device.

24. In a train controlled railway signal system, a track circuit including a source of energy, a circuit including a winding of two inductive couplings receiving energy from said source, a signal device receiving induced current from one of said inductive couplings, and a circuit connected in multiple with the track rail portion of said track circuit and inductively related to the second mentioned circuit, for restricting energy flow to said signal device when said track circuit is not shunted.

25. In a train controlled railway signal system, a track circuit including a source of energy, a circuit including a winding of two inductive couplings receiving energy from said source, a signal device receiving induced energy from one of said inductive couplings, and a circuit connected in multiple with the track rail portion of said track circuit and inductively related to the second mentioned circuit, for restricting energy flow to said signal device when said track circuit is not shunted and for increasing the energy flow to said signal device when said track circuit is shunted.

26. In a train controlled railway signal

system, a track circuit including a source of energy, a circuit including a winding of two inductive couplings receiving energy from said source, a signal device receiving induced energy from one of said inductive couplings, and a circuit connected in multiple with the track rail portion of said track circuit and inductively related to the second mentioned circuit, both windings of one inductive coupling coacting as choke coils to restrict the flow of current therethrough when said track circuit is not shunted, and both of said windings co-acting to reduce said choke coil effect when said track circuit is shunted.

27. A signal circuit controller comprised of an inductive coupling consisting of two windings, one of said windings connected in parallel with the track circuit of a railway signal system, and the other of said windings included in a circuit with a source of energy and a signal device, said windings at times co-operating to restrict the flow of energy to said signal device when the track rails are not shunted, and said windings co-operating to increase the flow of energy to said signal device when said track rails are shunted, said device arranged to be inoperative when said track circuit is not occupied by a train and to be synchronously operative when said track circuit is occupied by a train.

28. A train indication system comprised of a section of railway track, a source of energy, transformers for supplying said energy to said track at a plurality of points, impedance bonds connecting the rails of said track at and between the points of energy supply, and means inductively coupled to a circuit which is connected in parallel with said bonds for utilizing said energy to indicate the presence and movement of a train on said section of railway track.

Signed at Brooklyn, in the county of Kings and State of New York this 28th day of May, A. D. 1925.

GILBERT C. WHITNEY.
